UNITED STATES PATENT OFFICE.

WILLIAM HETTRICK SHANNON, OF ASTORIA, ILLINOIS.

RATCHET-WRENCH.

1,265,535.

Specification of Letters Patent.

Patented May 7, 1918.

Application filed February 5, 1918. Serial No. 215,504.

To all whom it may concern:

Be it known that I, WILLIAM H. SHANNON, a citizen of the United States, residing at Astoria, in the county of Fulton and State of Illinois, have invented a new and useful Ratchet-Wrench, of which the following is a specification.

This invention relates to wrenches and more particularly to ratchet wrenches.

10 An object is to provide a wrench with means for causing the automatic swinging of the wrench head about its pivotal axis to bring the jaws to any desired radial position with respect to the axis thereof so as to 15 facilitate the application of the wrench to a nut where it is difficult to reach the same.

A further object is to equip the wrench with means for frictionally holding the wrench head in the desired radial position 20 until a change in position is desired when, by a pressure of the hand of the operator, the said frictional holding means is released and the head is caused to automatically rotate under the braking action of the same, 25 until the desired position of the jaws is reached, when the pressure of the hand is released and the head will remain stationary and may be applied to a nut.

A full and complete understanding of the 30 invention may be obtained from a consideration of the following detailed description, taken in connection with the accompanying drawing forming a part of this specification; it being understood that while the drawing 35 shows a practical form of the invention, the latter is not confined to strict conformity therewith, but may be changed or modified, so long as such changes or modifications mark no material departure from the salient 40 features of the invention, as specifically pointed out in the appended claims.

In the drawing, in which like reference characters designate corresponding parts throughout the several figures:—

45 Figure 1 is a side elevation of the wrench, the head thereof being shown at one limit of its rotary movement.

Fig. 2 is a longitudinal sectional view thereof, the head being moved to its intermediate position, in alignment with the handle.

Fig. 3 is a view taken at right angles to Fig. 2.

50 Fig. 4 is a detail sectional view looking 55 in the opposite direction from that shown in Fig. 2.

Fig. 5 is a detail sectional view, taken on the line 5—5 of Fig. 2.

The invention comprises a handle preferably formed of metallic plates 1 and 2, of sufficient thickness and strength to withstand the strain to which the device is ordinarily subjected. These plates are spaced apart a suitable distance and are held in such position, at their outer ends, by a 60 spacing block 3 and a rivet 4, while the opposite ends are rounded and provided with suitable apertures for the reception of a rivet 5 having suitable shoulders for spacing the handle plates 1 and 2 a distance apart 70 equal to the thickness of the spacing block 3.

The said rounded ends of the handle plates are concentric with the axis of the rivet 5, and the plates are thus spaced apart for the purpose of housing certain movable parts 75 about to be described.

A wrench head 6 having, at one end, adjustable jaws 7 of any well known construction, is adapted to be mounted for rotation upon the rivet 5, the said head having an extended portion provided with a centrally located pivotal opening 8, arranged at the end of the head 6 opposite to the adjustable jaws 7. The said extended portion of the head is rounded concentrically to the pivotal 80 opening 8 and is provided with a series of ratchet teeth 9 extending around that end of the wrench head and describing an approximate semi-circle.

A pair of annular channels 10 and 11 are 90 provided in the wrench head 6 and extend substantially half-way through the same, the said channels being concentric with the pivotal opening 8. The outer diameter of the inner channel 10 is somewhat less than the 95 diameter of the adjacent rounded end of the handle plates 1 and 2, while the outer diameter of the outer channel 11 is somewhat greater, and, as a consequence, the said inner channel is completely housed while the outer 100 channel is partly exposed for a purpose to be described. (Fig. 5.)

By the construction disclosed annular walls 12 and 13 are defined between the inner channel 10 and the pivotal opening 105 8 and the inner channel 10 and outer channel 11, respectively, and said walls extend somewhat beyond the adjacent face of the wrench head 6 and are adapted to bear upon the inner face of the plate 1, and prevent 110 any lateral movement of the head 6 during its rotation about the pivot 5.

A coiled spring 14 is located within the inner channel 10 in surrounding relation to the annular wall 12, and has one terminal 15 bent to enter a suitable perforation in the plate 1, while the other end 16 of the coiled spring is similarly anchored in the rotary wrench head 6, as clearly illustrated in Fig. 5 of the drawing. The normal tendency of the spring 14 is to swing the wrench head to a position opposite to that shown in Fig 1 of the drawing, or to the right and it is necessary to manually force the head to the left, against the pressure of said spring, as illustrated in said figure.

15 A pivoted, hand-actuated pawl 17 is mounted between the plates 1 and 2, upon the rivet 18, which is located adjacent to the rotating head 6, and which may be suitably shouldered to rigidly space the plates 20 1 and 2 similarly to the rivet 5. The pawl 17 is angularly formed and provided with a suitable aperture 19 for the reception of the rivet 18, and has oppositely disposed bosses 25 surrounding the aperture 19 for centering the pawl 17 between the plates 1 and 2 and to act as a bearing for the said pawl. The intermediate portion of the pawl having the pivotal opening 19 extends substantially transversely of the handle plates 1 and 2 30 and between the same, while the finger-engaging portion 21 of the pawl, extends in the direction of, but at a slight angle to, the handle, and is sufficiently exposed beyond the adjacent edges of the plates 1 and 2 to 35 be readily actuated by the fingers of the operator to rock the pawl about its axis upon the rivet 18.

That end of the pawl 17 opposite the finger-engaging portion 21 is extended beyond the other side of the handle and is provided 40 with a tooth 22 directed toward the axis of rotation 5 of the wrench head 6, and in a position to engage the arcuate series of teeth 9, to arrest, when forced into such engagement by the hand of the operator, any movement of the head to the right, as viewed in Figs. 1 and 2 of the drawing.

An extension 23 is formed upon the toothed end 22 of the pawl 17 and is adapted 50 to enter the space between the adjacent faces of the plate 1 and the rotary wrench head 6, though it has been found advantageous to cut away that portion of the plate 1 located at the point where the extension 55 23 passes therein, as indicated at 24, so as to avoid any possible interference with the movement of the pawl about its axis.

The terminal of the extension 23 is provided with a lug 25 disposed at right angles 60 thereto, so as to extend into the outer channel 11 and to bear against the outer wall thereof when the said pawl is at one limit of its rocking movement and is out of engagement with the ratchet wheel. The extension 23 is of a length to permit of this

frictional engagement of the lug 25 with said wall, so as to serve as a friction brake, when the tooth 22 is free from engagement with the teeth 9 and, by a slight pressure on the portion 21 of the pawl, the said lug 25 70 is located free in the outer channel 11 and the wrench head may automatically swing to the right under the action of the spring 14.

An ordinary leaf spring 26 is mounted 75 between the plates 1 and 2 in a manner to bear against the inner side of the finger-engaging portion of the pawl 17; and to force the same outwardly into exposed position.

In the operation of the device, the jaws 7 are set to receive the nut to be turned, and the head 6 may be manually swung to the extreme left or to any position desired when, it will be seen, the spring 26, which is considerably stronger than the coiled spring 14, will maintain the terminal lug 25 in frictional engagement with the outer wall of the channel 11 and prevent the head 6 from being actuated by the said spring 14. If the nut be located in some inaccessible place, where only one hand may be used in the operation, the wrench head may be automatically moved to a more convenient position for engaging the nut, by a simple pressure of the fingers upon the portion 21 of the pawl 17, to ease up on the lug 25, and by releasing the finger-pressure, the head 6 will stop at the desired position.

When the jaws 7 have been applied to the 100 nut from any angle, the tooth 22 is then forcibly engaged with the adjacent tooth 9 by pressure on the finger-engaging portion 21 of the pawl 17, and the head 6 is then forcibly rotated about the axis of the nut 105 to turn the same on or off, as the case may be. It will be readily apparent that the opposite rotation of the nut may be accomplished by simply reversing the wrench.

From the foregoing it is thought the advantages of the wrench will be fully appreciated and it will be seen that a strong and durable device has been provided, having simple means for accomplishing the results sought. It is not absolutely necessary that 115 the channel 11 should be annular, as the full circle is not required to make an operative structure.

What is claimed is:—

1. A ratchet wrench comprising a handle, a wrench head pivoted thereto, said head having a curved channel formed therein concentric with its axis of rotation, ratchet teeth provided on the head outside the channel, a spring for automatically moving the 125 head about its axis in one direction, a toothed pawl for engagement with the ratchet teeth of the head for forcing the latter in the opposite direction, said pawl having an extension terminating in a lug enter- 130

ing the curved channel in the head, and a second spring bearing against the pawl for forcing the said lug against the outer wall of the curved channel to hold the head against movement by the first named spring.

2. A ratchet wrench comprising a handle having a rotary, toothed wrench head provided with nut-engaging jaws and concentric inner and outer channels formed in one 10 face thereof about its axis of rotation, a coiled spring mounted within the inner channel and having its ends connected to the head and the handle respectively for causing the head to rotate in one direction, 15 an arcuate series of ratchet teeth provided on the head in surrounding relation to the channels, a pawl pivotally mounted in the handle and having a tooth adapted to be manually pressed into engagement with the 20 ratchet teeth, a lug carried by the pawl and adapted to engage against the outer wall of the outer channel in the head, and a second spring, stronger than the first named spring

bearing against the pawl for maintaining the lug in such engagement.

3. A ratchet wrench comprising a handle, a wrench head pivoted thereto, a spring for automatically moving the head about its pivot in one direction, said head having ratchet teeth on its exterior, a pawl for engagement with the ratchet teeth, a spring for the pawl having a greater force than the spring for the head, and means provided on the pawl to engage the head when said pawl is out of engagement with the ratchet 30 teeth, said means serving as a friction brake to hold the head against movement by its spring.

In testimony that I claim the foregoing as my own, I have hereto affixed my signature in the presence of two witnesses.

WILLIAM HETTRICK SHANNON.
